UNITED STATES PATENT OFFICE.

ROBERT W. DE REIGN, OF SANTA BARBARA, CALIFORNIA.

MUSIC-LEAF TURNER.

Application filed August 13, 1927. Serial No. 212,716.

This invention relates to improvements in music leaf turners.

The principal object of this invention is to produce a mechanical device whereby the 5 individual sheets or pages of music may be mechanically turned over in a manner similar to that now accomplished manually.

Another object is to produce a device of this character which may be installed upon 10 an ordinary piano or upon a music rack.

A further object is to produce a device of this character which is free of springs and like mechanical parts which are easily deranged.

15 A still further object is to produce a device of this character which is neat in appearance and one which will not be objectionable to the eye.

Other objects and advantages will be apparent 20 during the course of the following description.

In the accompanying drawings forming a part of this specification and in which like numerals are employed to designate like 25 parts throughout the same,

Figure 1 is a front elevation of a music rack having my device applied thereto,

Figure 2 is a side elevation of the upper portion of my device,

30 Figure 3 is a cross section taken on the line 3—3 of Figure 4, and on an enlarged scale,

Figure 4 is a cross-section taken on the line 4—4 of Figure 3;

35 Figure 5 is a top plan view of the leaf engaging arms,

Figure 6 is a cross section taken on the line 6—6 of Figure 5 showing the sheet engaging clips, and

40 Figure 7 is an enlarged detail view showing a fragment of one of the clips.

It has been common practice for many years to turn the pages of music manually. This is oftentimes difficult to do without interrupting the playing, and I have therefore 45 produced a device for mechanically accomplishing this object.

In the accompanying drawings wherein for the purpose of illustration is shown a 50 preferred embodiment of my invention, the numeral 5 designates a box-like structure and the numeral 6 a backing secured thereto, against which the music book or composition is to be placed. The pages are designated 55 by the numerals 7, 8, 9 and 11. A plurality of shafts 12, 13 and 14 are journaled within

the box-like structure 5 and within suitable bearings 16 carried upon the back 6. These shafts are mounted in parallel relation as best shown in Figure 4.

60 Mounted upon shafts 12, 13 and 14 are gears 17, 18, and 19 respectively. The gear 17 is provided with an opening 21 therein so as to permit the shafts 12 and 13 to pass therethrough, while the gear 18 has an opening 22 to permit the shaft 14 to pass therethrough the purpose of which will be later seen. Mounted upon the box-like structure 5 are keys 23, 24, 26, and 27, 28, 29. The keys 23, 24 and 26 are secured upon rack 70 bars 31, 32 and 33 respectively, which rack bars each engage one of the gears 17, 18 and 19. The keys 27, 28 and 29 are secured to rack bars 34, 36 and 37 respectively. These rack bars also engage the gears 17, 18 and 19 but are positioned upon the opposite side of the gears from the rack bars 31, 32 and 33.

75 Secured to each of the keys is a cable for operating the keys through a foot movement. As all of these cables are identical in construction one will be described. This cable 38 is secured to the keys and passes over a pulley 39 thence downwardly as shown at 41, and is connected to a pedal 42 placed 80 conveniently for the operator to place his foot thereon.

85 Upon the upper end of each of the shafts is secured an arm 43 and as they are identical but one will be described. Each arm 90 carries a clip consisting of two plates 40 and 44 which have their lower extremities normally held in engagement with each other by a spring 46. The upper portion of these plates is provided with finger pieces 47 so 95 that they may be easily pressed toward each other for the purpose of engaging the sheet of music. These finger pieces also provide means whereby arms may be manually moved if desired.

100 The operation of the device is as follows:—

A sheet of music is placed upon the box-like structure after which each sheet is engaged by one of the clips, after which the 105 device is ready for operation.

Assuming that the buttons 27, 28 and 29 are all pressed in all of the sheets of music engaged by the clips will lie to the right of Figure 1. When it is desired to turn 110 the page, one of the buttons will be pushed as for instance the button 23 with the result

that the rack bar 31 will be pushed inwardly which will act upon the gear 17. This gear can rotate and due to the opening 21 formed therein the gear will make a half 5 revolution before it engages the shafts 13 and 14. This will throw the sheet from the right hand side of Figure 1 to the left hand side. The same operation on buttons 24 and 10 26 will accomplish the turning of the next succeeding sheets.

Should it be desired to return the sheets to their original position the buttons 27, 28 and 29 may be pressed with the result that the rack bars 34, 36 and 37 will function 15 in the same manner with the exception that a reverse movement of the gears 17, 18 and 19 will be accomplished. Should it be desired to turn the pages by employing the feet, one of the peddles will be pushed, for 20 instance the pedal connected to push button 23, the result being that a pull upon the cable 28 will be transmitted to the key. The remainder of the operation is identical to that above described.

25 It will thus be seen that I have produced a very simple device which will accomplish all of the objects herein set forth.

It is to be understood that the form of my invention herewith shown and described is to be taken as a preferred example of the 30 same and that various changes relative to the material, size, shape and arrangement of parts may be resorted to without departing from the spirit of the invention or the 35 scope of the subjoined claim.

Having thus described my invention, I claim:

In a music leaf turner, a box-like structure, a backing secured to said box-like structure, a plurality of parallel spaced shafts supported in said box-like structure, a gear secured to each of said shafts, certain of said gears having semi-circular openings therein, certain of said shafts extending through said openings, a rack engaging each of said gears, a push button secured to each of said racks at a point outside of said box-like structure, an arm secured to each of said shafts at its upper extremity, and a clip secured to each of said arms for the purpose specified.

In testimony whereof I affix my signature.

ROBERT W. DE REIGN.
